(57) **CLAIM**

The ornamental design for a foot massage tool, as shown and described.

DESCRIPTION

FIG. 1 is a front upper perspective view of a foot massage tool of Applicant's design;

FIG. 2 is a front elevational view thereof;

FIG. 3 is a rear elevational view thereof;

FIG. 4 is a first side elevational view thereof;

FIG. 5 is a second side elevational view thereof;

FIG. 6 is a top plan view thereof; and,

FIG. 7 is a bottom plan view thereof.

The broken lines depict portions of the foot massage tool that form no part of the claimed design.
